MEANS FOR PREVENTING ALTERATIONS
OF SERIAL NUMBERS

Theodore Torrison, Robbinsdale, Minn.

Application June 18, 1934, Serial No. 731,079

11 Claims. (Cl. 40—2.2)

This invention relates to means for discouraging the theft of machinery or apparatus such as motor vehicles, and the main object is to provide a device for containing, displaying, and protecting an identification serial number or other character whereby it becomes extremely difficult if not entirely impossible to change or alter such identifying symbol or character, and thereby eliminating all trace of previous ownership of the vehicle. And if an attempt is made to change the identification mark it can only be done by leaving evidence of tampering such as will immediately become apparent to a prospective purchaser or officer of the law upon casual inspection.

Further and more detailed objects, both as to purpose and structure, will be disclosed in the following specification, reference being had to the accompanying drawing, wherein:

20 Fig. 1 is a plan view of the device with a portion of the protecting cover housing broken away for purpose of illustration.

Fig. 2 is a sectional elevation on the line 2—2 in Fig. 1.

25 Fig. 3 is a sectional plan view on the line 3—3 in Fig. 2.

Fig. 4 is a detail, sectional elevation showing a modification in certain features of the invention.

30 Referring to the drawing more particularly and by reference characters, A designates generally the machine or apparatus to be identified, and in the case of a motor vehicle may be either the chassis frame or the engine block. For convenience in illustration I have shown the identification bearing member as being a portion of a channel iron frame member, the same having an upper flange 5, a lower flange 6, and an intermediate web 7, the latter of which is broken 40 away and vertically shortened in Fig. 2.

The serial number and other identification characters, designated generally by the numeral 8, are preferably ground or cut into the upper surface of a plate 9. Said surface is preferably unpainted, and, as an additional precaution against unauthorized tampering, may be provided with closely associated lines 10, which are engraved with an abrasive wheel, and which will by breaks or irregularities show, upon careful examination, if originally cut characters have been altered. These lines may also extend beyond the plate surface and to the adjoining frame flange surface, but are here illustrated as extending over the plate surface only.

55 The plate 9 is made of a comparatively hard

material such as tempered steel so that attempted alterations will be more difficult to execute and more readily detectable. The edges of the plate are preferably beveled, as at 11, to meet correspondingly beveled adjacent edges of the frame flange 5, provided with the plate recess, and these adjoining edges may be covered with patches or a strip of paint or similar material 12 to serve as a seal.

The plate 9 is provided with a pair of depending dovetail lugs 13 which are cast into a mounting block 14 which may be of relatively softer material. This block 14 may be secured in the machine to be identified in any suitable manner, but I have here illustrated it as being provided with a flange 15 by which it may be welded to the web 7 of the channel member 5—7 so as to become a permanent and rigid part of it. It will thus be understood that the plate 9 is cast into so as to form a part of the block 14, and that to 10 secure the plate in its proper position it is necessary to insert it upwardly into the recess in the frame flange 5, and when in this position the welding of the block 14 to the frame is effected.

Upon its upper surface the plate 9 is provided 15 with a series of centering pegs 16 upon which is seated a casing 17 formed of glass or other suitable material which is sufficiently transparent so that the characters or identifying symbols 8 may be read through it. The casing 17 is provided 20 when molded with a bridging member 18 which preferably extends lengthwise through the material forming the top of the casing, and serves to connect two posts 19 which extend downwardly 25 within the side and end walls of the casing and 30 project into holes drilled in the lugs 13. The lower ends of the posts 19 are tubular in form 35 and may also be radially split so that they may easily be spread or flared outwardly so as to become permanently and non-removably anchored 40 in the lugs 13. To this end the post holes are widened at their lower extremities, as shown at 45 20, and before the posts are inserted and forced downwardly into place a small member such as a bearing ball 21 is first inserted so that as the 45 posts are forced into place the tubular and split lower ends will be automatically spread into anchoring position so as to effect the permanent attachment referred to. It may here be noted that if the post holes are to be formed in the 50 plate structure before the same is cast into the block 14, it will be necessary to stop the flow of block metal into the post holes, and for that reason I have provided the lower ends of the 55 lugs with shields 22 which may be of thin sheet

metal, and are fitted in place over the lugs so as to close the post holes against entry of the molten metal therein.

- A modification of the anchoring means is shown in Fig. 4, wherein it is illustrated how post holes in the lugs may be eliminated by placing socket members 23 above the plate surface and connecting them thereto by webs or standards 24, which are cast integrally therewith. The advantage of this structure over that shown in Fig. 2 is that it positively precludes the removal of the anchor posts by drilling upwardly into the post holes from the bottom surface of the block 14, except of course by destroying the standards 24, in which event the tampering would immediately be noticeable through the casing 17.

The anchor posts 19, as already indicated, form a fixed part of the casing 17, and as the lower ends of the posts engage the balls 21 and spread outwardly the lower edges of the casing proper simultaneously move down upon the centering pins 16 and become firmly and closely seated against the upper surface of the plate.

To prevent fracturing of the casing it is of course necessary to apply the hammering or forcing pressure directly upon the metallic anchor posts, and for that reason the upper ends of the posts project beyond the upper surface of the casing 17, as indicated at 25. These exposed ends are reduced in size, as illustrated, and the purpose of this arrangement is to prevent removal of the casing by drilling downwardly into the posts 25 so as to sever its connection with the lower portions of the posts. It will be seen that if the posts were of the same diameter throughout their length, then a drill of the same diameter might be used effectively to remove the casing. However, with the exposed ends of the posts of reduced size, a drill of such lesser diameter cannot be effectively employed to shear the anchoring connection without at least first rupturing the casing material, and when this is done it provides the necessary visible evidence that tampering has been attempted.

It may here also be noted that as a further effective measure to discourage tampering, it may be advisable to secure upon the under surface of the casing top or even imbed in the casing material, a seal of distinctive character that would be very difficult to reproduce; and would thus further discourage tampering inasmuch as there would be a lesser tendency for inclination to remove the casing entirely and replace it by a substitute or counterfeit casing.

It may here further be noted that the casing 17 is preferably secured after the plate 9 has been mounted in its recess, and that at least one wall of the casing will cover one joint or seam between the plate 9 and the adjacent flange portion 5, as indicated at 26, so that it will be extremely difficult to remove the identification plate downwardly through the recess, assuming of course that the block 14 has first been cut away or detached from the channel member 5-7. It will thus be seen that very effective measures are provided for the safeguarding of the machine identifying number, and consequently will greatly discourage the theft of automobiles by such persons or groups of persons as make a practice of stealing motor vehicles, changing the serial numbers thereon, and then reselling the machines.

Inasmuch as the casing 17 must be of transparent material such as glass, and is therefore subject to accidental breakage, I have provided a housing 27 which entirely encloses the casing

and is detachably secured to the frame 5-7 as by bolts 28 and thumb screws 29.

It is understood that suitable modifications may be made in the structure as disclosed, provided such modifications come within the spirit and scope of the appended claims. Having now therefore fully illustrated and described my invention, what I claim to be new and desire to protect by Letters Patent is:

1. An identification device for motor vehicles and the like comprising a plate adapted to be permanently fixed to the vehicle and having an exposed surface bearing identification characters, a casing superimposed over said plate surface and through which said characters may be read, and means including anchor posts for permanently attaching the casing to the plate, said plate having downwardly flared sockets for receiving the lower ends of the posts, and means for spreading such lower post ends laterally when they are forced into the sockets.

2. An identification device for motor vehicles and the like comprising a plate adapted to be permanently fixed to the vehicle and having an exposed surface bearing identification characters, a casing superimposed over said plate surface and through which said characters may be read, and means including anchor posts for permanently attaching the casing to the plate, said plate having downwardly flared sockets for receiving the lower ends of the posts, and means for spreading such lower post ends laterally when they are forced into the sockets, said last mentioned means including a spreader member disposed centrally of and within each of the sockets.

3. An identification device for motor vehicles and the like comprising a plate adapted to be permanently fixed to the vehicle and having an exposed surface bearing identification characters, a casing superimposed over said plate surface and through which said characters may be read, and means including anchor posts for permanently attaching the casing to the plate, said plate having downwardly flared sockets for receiving the lower ends of the posts, and means for spreading such lower post ends laterally when they are forced into the sockets, said last mentioned means including a spreader ball in each socket.

4. An identification device for motor vehicles and the like comprising a plate adapted to be permanently fixed to the vehicle and having an exposed surface bearing identification characters, a transparent casing arranged on said plate surface and through which said characters may be read, and means permanently connecting the casing and plate including a post extending from one and a socket in the other receiving the post, and means for spreading the post in the socket to form a connection permanent except by mutilation of some part of the device.

5. An identification device for motor vehicles and the like comprising a plate adapted to be permanently fixed to the vehicle and having an exposed surface bearing identification characters, a transparent casing arranged on said plate surface and through which said characters may be read, and means permanently connecting the casing and plate including a post extending from one and a socket in the other receiving the post, and means for spreading the post in the socket to form a permanent connection therebetween, said casing having recesses and said plate having centering pins engageable in the recesses.

6. An identification device for motor vehicles and the like comprising a plate permanently fixed

- to a part of the vehicle and having an exposed surface bearing identification characters, a transparent casing arranged on said plate surface and through which said characters may be read, and 5 means permanently connecting the casing and plate including a post extending from one and a socket in the other receiving the post, and a removable housing attached to said vehicle part and enclosing the casing.
- 10 7. An identification device for motor vehicles and the like comprising a plate adapted to be permanently fixed to the vehicle and having an exposed surface bearing identification characters, a casing superimposed over said plate surface 10 and through which said characters may be read, and means including anchor posts for permanently attaching the casing to the plate, said plate having downwardly flared sockets for receiving the lower ends of the posts, and means 15 for spreading such lower post ends laterally when they are forced into the sockets, said casing being of transparent fracturable material, and said posts extending outwardly of the casing for receiving pressure to force them into 20 the sockets without fracturing the casing.
8. An identification device for motor vehicles and the like comprising a plate adapted to be permanently fixed to the vehicle and having an exposed surface bearing identification characters, a casing superimposed over said plate surface and through which said characters may be read, and means including anchor posts for 25 permanently attaching the casing to the plate, said plate having downwardly flared sockets for receiving the lower ends of the posts, and means for spreading such lower post ends laterally when they are forced into the sockets, said posts having exposed ends projecting outwardly of the casing and reduced in cross sectional area where thus projected. 5
9. An identification device for motor vehicles and the like comprising a plate adapted to be permanently fixed to the vehicle and having an exposed surface bearing identification characters, 10 a casing superimposed over said plate surface and through which said characters may be read, a pair of posts extending from the casing for anchorage attachment to the plate, and a bridging member connecting said posts, said bridging member being imbedded within the material of the casing. 15
10. A device of the character described comprising a base block for permanent attachment to a vehicle, an identification plate having lugs 20 fixed in the material of the block, and a fracturable, transparent casing secured over the plate, said casing and plate being secured together by anchorage posts permanently fixed in both. 25
11. A device of the character described comprising a base block for permanent attachment to a vehicle part, an identification plate having lugs fixed in the material of the block, and a fracturable, transparent casing secured over the plate, said casing and plate being secured together 30 by anchorage posts permanently fixed in both, and a removable housing attached to said vehicle part and enclosing the casing.

THEODORE TORRISON.
